BOTTOM FOR DRUM STAND

Josephus B. Thompson, deceased, late of Covington, Ohio, by K. E. Stade, administrator, Covington, Ohio, assignor to Columbia Broadcasting System, Inc., New York, N.Y., a corporation of New York

Continuation of design applications Ser. No. 13,915 and Ser. No. 13,919, both Oct. 9, 1968. This application June 24, 1969, Ser. No. 18,397

Term of patent 14 years

Int. Cl. D17—04

U.S. Cl. D56—1

Dec. 219,713

PAGE 2

FIG. 3.

FIG. 4.

FIG. 1 is a perspective view of a bottom for a drum stand, showing a first embodiment of my new design;

FIG. 2 is a side elevational view of the embodiment shown in FIG. 1, the opposite side, not shown, being substantially a mirror image thereof;

FIG. 3 is a front elevation of the embodiment shown in FIG. 1;

FIG. 4 is a bottom plan view of the embodiment shown in FIG. 1;

FIG. 5 is a perspective view of a bottom for a drum stand, showing a second embodiment of my new design;

FIG. 6 is a side elevational view of the embodiment shown in FIG. 5;

FIG. 7 is a rear elevation of the embodiment shown in FIG. 5; and

FIG. 8 is a bottom plan view of the embodiment shown in FIG. 5.

This application is a continuation of design patent applications Ser. No. D. 13,919 and Ser. No. D. 13,915, both filed Oct. 9, 1968, now abandoned.

What is claimed is:
The ornamental design for a bottom for drum stand, substantially as shown and described.
